UNITED STATES PATENT OFFICE.

MICHAEL BENEDICT, OF NEW YORK, N. Y.

VENDING MACHINE.

Application filed June 17, 1926. Serial No. 116,587.

This invention relates more particularly to a class of apparatus for dispensing articles.

My invention has for its object primarily to provide a slot machine designed to be employed in public places and elsewhere for permitting fancy post cards, good luck prophesying cards and other suitable articles of merchandise to be sold in a manner whereby a person on inserting into the machine a coin of a given value will cause the figure of a living object to operate for picking-up and dispensing the articles singly with each deposit of the coin in the machine. The figure may be of a form representing a bird, animal or other living object which is so positioned that the person using the coin may observe the novel and interesting manner in which the figure operates, and which by reason of its lifelike appearance and action in its movements will serve to attract attention thereto.

The invention consists essentially of a casing having a chute leading into its interior, and in the casing is a movable figure of a living object, such as a bird, animal, fish or other object. Power driven mechanism is provided in the casing for being made effective by a coin of a determined value being inserted in and ejected from the chute for causing the figure to rotatively move in downward and upward directions and to cause the figure to rotatively move the second time in downward and upward directions. Associated with the figure is means which is operative by the mechanism for causing the mouth of the figure to open and close for picking-up an article in the casing when the figure is first moved a determined downward distance and to subsequently cause the mouth of the figure to open for discharging the article with the second downward movement of the figure. Possession of the article when discharged may be taken by the person who used the coin, and means is provided for being operated by the mechanism to shut-off its power with the delivery of the article by the figure.

With these and other objects in view, the invention will be hereinafter more fully described with reference to the accompanying drawings forming a part of this specifica-

tion in which similar characters of reference indicate corresponding parts in all the views, and will then be pointed out in the claims at 55 the end of the description.

In the drawings, Figure 1 is a front elevation of one form of slot machine embodying my invention.

Fig. 2 is a side elevation of the machine. 60

Fig. 3 is an enlarged fragmentary sectional view, partly broken away and partly in elevation, taken through the machine.

Fig. 4 is a fragmentary sectional view, partly in elevation and partly broken away, 65 taken on the line 4-4 of Fig. 3.

Fig. 5 is a fragmentary sectional view, partly broken away and partly in elevation, taken on the line 5-5 of Fig. 3.

Fig. 5^A is an enlarged fragmentary sectional view taken on the line 5^A-5^A of Fig. 3. 70

Fig. 6 is an enlarged fragmentary sectional view, partly in elevation, showing the parts of the machine for closing and opening the circuit to operate and shut-off the power to the operating mechanism after being operated for a given period of time, and which shows a diagrammatic view of the electric circuit. 75

Fig. 7 is an enlarged fragmentary sectional view, partly in elevation, showing the stop parts of the machine in a different position. 80

Fig. 8 is an enlarged fragmentary sectional view, partly in elevation, showing the stop parts in still a different operative position. 85

Fig. 9 is an enlarged side elevation of the supporting plate of the figure of a living object used in the machine for dispensing 90 articles.

Fig. 10 is a similar view showing the plate of the figure in a different tilted position.

Fig. 11 is a similar view of the plate of the figure showing it in another tilted position. 95

Fig. 12 is a similar view of the plate of the figure showing it in still another tilted position, and

Fig. 13 is an enlarged fragmentary sectional view taken on the line 13-13 of Fig. 7, and which shows a plan of the circuit closing post or pin of the trip switch used in the machine. 100

The machine has a casing 10 which may be of any appropriate size and shape, though the casing illustrated is substantially rectangular to provide a bottom wall 11, front wall 12, side walls 13, 14 rear wall 15 and an upper wall 16. The casing is divided into a lower chamber 17 and an upper chamber 18 by a partition 19 which is supported across the center of the interior of the casing. The 10 casing may be supported at a suitable elevation on a number of legs or standards 20, and the part of the front wall 12 above the partition 19 is preferably cut away to provide an open front to the upper chamber of 15 the casing. At the rear half of one of the sides of the upper chamber 18 may be a subchamber 21, Figs. 3 and 5, which is formed by an upright substantially L-shaped partition 22 extending between the cross partition 20 and the upper wall 16 and also extending from the side wall 13 to the rear wall 15. At the rear half of the opposite side of the upper chamber 18 may be a second subchamber, not shown, which is formed by 25 an upright substantially L-shaped partition 24 extending from the cross partition 19 to the upper wall 16 and also extending from the side wall 14 to the rear wall 15 of the casing. Above the rear half of the cross 30 partition 19 between the subchambers may be a platform 25 which is formed by a partition of somewhat the shape of an inverted L which extends between the upright partitions 22, 24. On the inner face of the rear 35 wall 15 above the platform 25 and between the subchambers may be a mirror 26, and the inner faces of the walls as well as the platform may be fancifully decorated if desired in order to present an attractive appearance to persons. In parts of the partition 19 at the front of the casing are two spaced openings 27, 28, and leading from a slot 29 at one side of the upper portion of the front wall 12 of the casing is a chute, as 40 30, which extends downwardly on an incline into lower chamber 17 of the casing for receiving and delivering a coin of a given value. The lower end of the chute 30 is fastened, at 31, to a plate 32 which extends longitudinally from the front wall toward 45 the rear wall of the casing, and the lower open end of the chute is in register with an opening 33 in the plate 32. Under the plate 32 is a removable drawer or box 34, Fig. 6, 50 of a suitable size and shape for receiving the coin discharged from the chute, and in one side of the part of the chute above the plate 32 is a slot or hole 35. The second end of the plate 32 is supported on one end of a bracket 36 of substantially the shape of 55 an inverted U to provide two spaced legs 37, 38 and a spanning member 39. The U-shaped bracket 36 is of such a length that it extends nearly across the width of the lower 60 chamber 17, and the bracket is fastened, at 65

39^a, to the bottom wall 11 of the casing about midway between the front wall and rear wall of the casing.

In the subchamber 21 of the upper chamber 18 of the casing 10 is a fixed frame 40 composed of two spaced upright substantially rectangular plates 41, 42 which may be bolted together, as at 43, and the central part of each of these rectangular plates may be cut-out, as at 44. Across the central part 70 of the plate 42 of the frame 40 may be a bar, as 45, having its ends fastened, at 46, to the plate, and projecting into the cut-out 44 of the plate 42 above the bar 45 may be a lug 47. On the inner face of one of the 75 walls of the L-shaped partition 22 of the subchamber 21 is a bearing 48, Fig. 5^a, and on the opposite face of this wall of the partition is a second bearing 49 having its bore in register with a hole in the partition and 80 in register with the bore of the bearing 48. A tubular shaft 50 has one of its ends journaled in the bearings 48, 49 so that this end of the bearing protrudes into the subchamber 21 beyond the plate 41 of the frame 40, and this tubular shaft is of such a length 85 that its second end terminates in the center of the upper chamber 18 of the casing above the platform 25.

On the end of the tubular shaft 50 in the upper chamber 18 of the casing is mounted the figure of a living object, as 51, which in the drawing is shown as representing a bird, though the object may simulate an animal or fish or other animated object. The figure 90 of the bird 51 has a hollow body 52 which is divided lengthwise into halves 53, 54, and these halves are mounted on a central plate 55 of a shape corresponding to the general 95 contour of the hollow body of the figure. One of the feet, as 56, of the object 51 is formed on the plate 55, and this foot is tubular to provide a passage 57 leading toward the center of the body portion 58 of the plate 55. The mouth or beak or bill of 100 the object or bird has one member, as 59, integral with and projecting from the head portion 60 of the plate. The second member, as 61, of the bill of the object or bird is preferably in the form of a tapered finger 105 or short bar having its central part pivoted, at 62, to the central part of the head portion 60 of the plate 55 so that one end of the tapered bar or second member of the bill is pivotally movable toward and from the 110 member 59 of the bill. The feet 56 of the plate 55 of the object is welded or otherwise secured to the upper part of the end of the tubular shaft 50 above the platform 25 of 115 the casing, and the passage 57 of the feet leads into the interior of the tubular shaft. When the shaft 50 is revolved accordingly 120 the object will rotatively move or tilt in downward and upward directions toward and from the part of the casing in front of 125 130

the platform 25, as will be later explained. As shown, the second foot of the object 51 overhangs the free end of the tubular shaft 50, and extending from the partition 24 of 5 the casing may be a fixed tube 63 having its free end abutting against the end of the tubular shaft 50, the second foot of the bird being above this tube 63.

Interiorly of the upper chamber 18 of the 10 casing and on the top of the partition 19 is a magazine 64 for holding post cards, as A, or fortune-telling cards or other suitable articles of merchandise. The magazine 64 is preferably substantially rectangular in 15 cross section to provide two spaced side walls 65, 66 and a top wall 67. The side walls 65, 66 are fastened, at 68, to the partition 19 of the casing. These walls of the magazine 64 extend across the partition 19 20 under the central portion of the platform 25, and the walls are of lengths so that they extend beyond the front of the platform and in proximity to the open front of the upper chamber 18 of the casing. The forward end of the walls 65, 66, 67 of the magazine is closed by an inclined end wall 69. In the top wall 67 of the magazine adjacent 25 the end wall 69 is a receiving inlet or opening 70 in register with the delivery outlet or opening 28 of the partition 19 of the casing, and in the top wall of the magazine in closely spaced relation to the receiving opening 70 is a delivery outlet or opening 71 in register with the opening 27 of the partition 30 35 19. The part of the magazine extending beyond the front of the platform 25 and which includes the receiving opening 70 and the delivery outlet 71 may be considered as a box like portion. The receiving opening 70 and delivery outlet 71 are both positioned so 40 that the object 51 when lowered and raised to different angles, as will be subsequently explained, will pick-up the articles delivered through the outlet 71 and afterward deliver 45 the articles for being dispensed through the opening 70. On the upper wall 67 of the magazine 64 at the rear edge of the delivery outlet 71 is an upward extending guide plate 72, and in the side walls 65, 66 are journaled 50 the ends of a shaft or rod 73 which extends across the interior of the magazine. On the central part of the shaft 73 is held the lower end of a rod 74 which extends upwardly through the delivery outlet 71 with 55 its upper end normally disposed for movably contacting with the guide plate 72, and on the ends of the shaft 73 is held one of the ends of a pair of weights or bars 75, 75^a which are disposed on downward inclines 60 for serving to rotatively hold the shaft 73 for retaining the upper end of the rod 74 in yielding contact with the guide plate 72 for movably holding the articles against the guide plate when delivered through the outlet 71. In the upper parts of the side walls

65, 66 of the magazine 64 and under the rear edge of the receiving inlet 70 are journaled the ends of another shaft 76. On the central parts of this shaft are held the lower ends of two spaced rods 77, 77^a which protrude upwardly on rearward inclines through the inlet 70 of the magazine. The rods 77, 77^a are of such lengths that their upper ends terminate above and on a vertical line similar to the end of the rod 74, 75 and on the lower parts of the rods 77, 77^a may be a cross plate, as 78. On the ends of the shaft 76 are held one of the ends of two weights or bars 79, 79^a which serve to rotatively hold the shaft 76 to maintain the rods 80 85 77, 77^a and the cross plate 78 normally in their rearward inclined positions. Extending from the side walls 65, 66 crosswise of the center of the interior of the magazine are two spaced alined plates 80, 81. Between the central part of the plate 80 and the top wall 67 of the magazine is a plate or side wall 82, and between the central part of the plate 81 and the top wall 67 is another plate or side wall 83. The plates or 90 walls 80, 81, 82, 83 are of lengths to provide a box or chamber, as 84, which extends from the rear of the casing to the delivery outlet 71 of the top wall 67 of the magazine for holding the articles to be dispensed 95 from the machine. The central parts of the side walls 82, 83 of the box 84 are slotted lengthwise respectively at 85, 86, and in the box 84 is a slidable substantially rectangular pusher plate 87 having extending in opposite directions from its ends two apertured lugs 88, 89 which are slidably disposed through the slots 85, 86 of the side walls 82, 83 of the chamber 84 of the magazine. In the apertured lug 88 of the pusher plate 87 100 is fastened one end of a line or cable 90 which extends exteriorly of the chamber 84 to the forward part of the magazine, and this cable is trained over a pulley 91 held on one end of a shaft 92 having its end parts 105 journaled in the slotted side walls 82, 83 of the chamber 84. In the apertured lug 89 of the pusher plate 87 is attached one end of a line or cable 93 which also extends exteriorly of the chamber 84 to the forward part 110 of the magazine, and the cable 93 passes over a pulley 94 held on the shaft 92. The cables 90, 93 are of such lengths that their second ends pass through the opening 28 of the partition 19 into the lower chamber 17 115 120 of the casing. Held on the second ends of the cables is a bar, as 95, of sufficient weight for exercising sufficient pull on the cables to cause the pusher plate 87 to move in the chamber 84 of the magazine for yieldingly feeding the articles or cards A singly in succession to the part of the chamber for being ejected when the machine is operated. When it is desired to supply the chamber 84 125 with the articles or cards, the pusher plate 130

87 is moved rearwardly and out of the chamber against the pull of the weight or bar 95 and the cards are then suitably arranged in the chamber 84 for being fed to the outlet 71 of the top plate 67 of the magazine.

The machine is operated by power driven mechanism, as B, for rotating the tubular shaft 50 to move the object 51 downwardly and upwardly, and the mechanism B includes the parts or means C for delivering each of the cards A to be dispensed by the object 51. The mechanism also includes the parts D for opening and closing the mouth of the object 51 to pick-up and discharge the cards, and included in the mechanism are the parts or means E for shutting-off the power to stop the mechanism after the machine has operated for a determined period or following the delivery of each of the cards. The mechanism B has a drive shaft 96 which is journaled in an arm, as 97, extending from the leg 38 of the U-shaped bracket 36 in the lower chamber 17 of the casing. On the drive shaft 96 is a worm gear 98, and in mesh with this worm gear is a worm 99 held on the shaft of a motor 100 which may be of any suitable type adapted to be electrically driven from any source of current supply, such as a battery 101 through the medium of a circuit, as 102, Fig. 6. On the drive shaft 96 is a pulley 103 over which is trained a belt 104, and this belt also passes over a pulley 105 held on a stud 106 journaled in an upright plate or bracket 107 which is secured, at 108, to the lower wall 11 of the casing. Also on the stud 106 is a bevel gear 109 in mesh with a bevel gear 110 which is held on the lower end of a vertical shaft 111 having its lower end journaled in the bracket 107. This vertical shaft 111 extends through a hole in the cross partition 19 and into the subchamber 21 of the casing. The upper end of the shaft 111 is journaled in a bracket, as 112, Fig. 5, which is fixed on the wall 22 of the subchamber 21, and at the upper end of the shaft 111 is a worm 113 which meshes with a worm gear 114 held on a stud, as 115, having its ends journaled in the bracket 112 and in the bar 45 of the plate 42 of the fixed frame 40 in the subchamber 21.

On the stud 115 is a sprocket wheel 116 of the parts C for delivering the cards A singly through the outlet 71 of the magazine 64, and passing over the sprocket wheel 116 is a sprocket chain 117. This sprocket chain leads through openings in the partition 19 and extends into the lower chamber of the casing where it is trained over a sprocket wheel 118 held on a stud 119 which is journaled in a bearing, as 120, fastened, at 121, to the bottom wall 11 of the casing. Also on the stud 119 is held a disk 122, and the lower end of a rod 123 is eccentrically

pivoted, at 124, to this disk. The upper end of the rod 123 is hinged, at 125, to the lower end of an ejector or plate 126 for feeding the cards A singly through the outlet 71, and the ejecting plate 126 is movable in the 70 grooves or spaced between two pairs of spaced vertical guide plates 127, 127^a which extend from the partition 19 alongside of the ends of its opening 27 across the end of the chamber 84 of the magazine. 75

On the stud 115 is a gear 128 in mesh with a gear 129 held on a shaft 130 which is disposed in the tubular supporting shaft 50 of the object or bird 51. One of the ends of the shaft 130 is journaled in the lug 47 of the plate 42 of the frame 40 in the subchamber 21, and this shaft is of such a length that it extends through the tubular shaft with its second end journaled in a block bearing, as 131, which is fixed in the end of the tube 63 that abuts against the tubular shaft 50, as shown in Fig. 5. The shaft 130 is included in the parts D of the mechanism B for opening and closing the mouth or bill of the object or bird 51, and on the shaft 130 under the passage 57 of the leg 56 of the object is held the center of a rotary cam 132 of substantially an elliptic shape, and at one of the apices of the cam is a tooth, as 133. In the passage 57 of the leg 56 of the object 51 is a reciprocable rod 134 which extends toward the center of the body portion 58 of the plate 55, and to the part of the body portion of the plate in proximity to the leg 56 is pivoted, at 135, the apex of a substantially V-shaped lever 136. One of the arms of the lever 136 is in the path of movement of the rod 134. A rod 137 has one of its ends movably engaging the second arm of the V-shaped lever 136, and this rod 137 is slidably disposed through two spaced eyes or lugs 138, 139 which protrude from the body portion 58 of the object. The second end of the rod 137 is pivoted, at 140, to the end of the bar or bill 61 in the head 60 of the plate 55 of the object. On the rod 137 between the eyes 138, 139 is a fixed collar 141 and encircling the rod 137 between the collar 141 and the eye 139 is a spiral spring 142 which is tensioned for normally serving to force the collar and the rod 137 yieldingly in a direction toward the V-shaped lever 136 for pivotally moving the free end of the member 61 into engagement with the member 59 of the beak or bill of the object. On the end of the tubular shaft 50 in the subchamber 21 of the casing 10 is held the free end of one arm 143 of an approximately L-shaped bracket 144 which is so disposed that its other arm 145 overhangs the stud 115 of the gear 128. Protruding laterally from the free end of the arm 145 of the bracket 144 is a follower pin 146 in movable engagement with the edge of a cam plate or controller 147 which is eccentrically 125 130

held on the stud 115 for operating the parts D to cause the mouth of the object 51 to open and close. The controlling cam 147 has a body portion 148 of an irregular substantially an ovoidal shape to provide a somewhat straight edge part, as 149, opposite to the stud 115, and protruding laterally from the body portion 148 in proximity to the stud 115 a tapered hump or extension, as 150, having a partly circular free end. The controlling cam 147, cam 132 of the shaft 130 and L-shaped bracket 144 with its pin 146 are proportioned so that when operated the tubular shaft 50 will be rotated to rotatively move the object 51 downwardly at which time the mouth of the object will be opened and closed. The object will then be rotatively moved upwardly and afterward moved downwardly the second time. With the second forward movement the mouth of the object will again be opened and closed, as will be hereinafter more fully explained.

The parts E of the mechanism D serve to start the operation of the machine with the delivery of the coin in the chute 30, and these parts also serve to stop the machine after operating for delivering each of the articles or cards A. The parts E include the operating lever or bar 151 which is fulcrumed, at 152, to the upper end of an upright bracket 153 having its lower end fastened, at 154, to the plate 32 of the casing about midway between the chute 30 and the leg 37 of the U-shaped bracket 36. One end of the operating lever is angularly bent, at 155, inwardly of the slot 35 and cross-wise of the passage of the chute for being in the path of a coin passing through the chute. The other end of the lever 155 is fixed to the bolt 156 of a trip switch, as 157, which is interposed in the electric circuit 102 for closing the circuit to operate the motor 100 for operating the machine and to also open the circuit for shutting-off the power to the motor to stop the operation of the machine. The bolt 156 protrudes from the lower end of an upright bar, as 158, and to this bar is fastened, at 159, one of the side edge parts of a substantially rectangular insulating plate 160 having its other side edge portion projecting beyond the bar 158. On the free edge of the projecting portion of the insulating plate 160 is fastened by a bolt 161 and by a binding post 162 a conductive plate 163 which may be of an L-shape in cross section so that one of its arms overlaps the free side edge of the insulating plate. On the bolt 156 and spaced from the bar 158 is pivoted the elbow of a trip lever 164 which is preferably of an obtuse angular shape to provide a downwardly inclined leg, as 165, and a second leg or arm 166 which protrudes on an upward incline toward the binding post 162 of the insulating

plate 160. The leg 165 of the trip lever 164 is tapered toward its free end, and to the arm 166 of the trip lever is fastened, at 167, an insulating plate 168 which extends laterally from the arm 166 and beyond the insulating plate 160 of the upright bar 158 of the switch 157. At the upper end of the insulating plate 168 is a binding post 169 which extends across the space between the insulating plates 168 and the insulating plate 160. To the upper end of the arm 166 of the lever 164 is attached, at 170, one end of a spring, as 171, having its other end attached, at 171^a, to the upright bracket 153 which supports the operating lever 151, and this spring is tensioned for normally forcing the arm 166 of the lever 164 yieldingly in a direction toward the bracket 153 so that the tapered leg 165 of this lever will be yieldingly held normally in an opposite direction. On the U-shaped bracket 36 in the lower chamber 17 of the casing is a bar 172 having its central part pivoted, at 173, to the upper plate 39 of this bracket. The bar 172 is of such a length that its ends terminate at the legs 37, 38 of the bracket 36, and the free end of the tapered leg 165 of the lever 164 is in movable contact with the part of the upper face of the bar 172 above the leg 37 of the bracket 36, as shown in Figs. 6, 7, 8. The portion of the upper face of the end of the bar 172 in opposed relation to the bracket 153 is grooved, at 174, to provide a stop shoulder 175 for being engaged by the leg 165 of the trip lever 164, and to this grooved end of the bar 172 is attached, at 176, one end of a spring 177 having its other end attached, at 178, to the bracket 153. The spring 177 is tensioned for normally forcing the grooved end of the bar 172 yieldingly in a direction toward the bracket 153. To the other end of the bar 172 is pivoted, at 179, one end of a link 180, Fig. 3, and the other end of this link is pivoted, at 181, to the upper end of a vertically disposed lever bar 182 having its central part pivoted, at 183, to the projecting arm 97 of the leg 38 of the U-shaped bracket 36. The lower end of the lever bar may be beveled, and this beveled end of the lever bar movably engages the peripheral edge of a disk cam, as 184, held on the shaft 119 adjacent the sprocket wheel 118 over which is trained the sprocket chain 117. Protruding from part of the edge of the disk cam 184 is a tooth, as 185, which is normally engaged by the beveled lower end of the lever bar 182. As will be later explained, the disk cam is of such a circumference and serves with each of its complete revolutions to operate the lever bar 182, link 180 and the bar 172 for cutting-off the power to the motor 100 for stopping the machine after being operated for a given period of time.

The electric circuit 102, Fig. 6, has a wire

186 leading from one terminal of the battery 101 to one terminal of the motor 100. A wire 187 leads from the second terminal of the motor to the binding post 162 of the conductive plate 163 of insulating plate 160 of the trip switch 157. A wire 188 leads from the second terminal of the battery 101 to a contact 189 adapted to be engaged by a suitable switch 190 for closing the circuit, 10 and a wire 191 leads from the switch 190 to the binding post 169 of the insulating plate 168 of the trip lever 164.

When the machine is not in operation the figure 51 of the living object, the controlling cam 147, the L-shaped bracket 144 with its follower pin 146 and the toothed cam disk 184 are in their respective positions, as shown in Fig. 3. To operate the machine a coin of a given value is inserted in the entrance 15 29 of the chute, and during the passage of the coin through the chute into the receiving box 34 the coin will contact with the bent end 155 of the operating lever 151. This bent end of the operating lever 151 will 20 move downwardly in the chute, and the other end of the lever will move upwardly to cause the switch 157 to likewise move upwardly. With the upward movement of this switch the tension of the spring 171 will 25 cause the trip lever 164 to move from its normal position, as shown in Fig. 6, with its arm 165 engaging the stop shoulder 175 of the groove 174 of the bar 172 to the position, as shown in Fig. 7, with the arm 165 30 of the lever 164 resting on the part of the upper face of the bar 172 rearwardly of the groove 174. With this movement of the trip lever 164 the binding post 169 will also engage the conductive plate 163 of the insulating plate 160 of the switch 157. Following 35 the closing of the switch 190 on the contact 189, the circuit 102 will be closed from one terminal of the battery 101 over wire 188, through switch 190, over wire 191, through 40 the binding post 169, through the conductive plate 163 and over wire 187 to one terminal of the motor 100. From the second terminal of the battery 101 the circuit will be completed over wire 186 to the other terminal 45 of the motor. The motor will then be energized, and with the rotation of its drive shaft the worm 99 and worm gear 98 will be driven for driving the shaft 96. With the driving of the shaft 96 the pulley 103 50 will be rotated to drive the sprocket chain 104 for revolving the pulley 105. The stud 106, and bevel gears 109, 110 will then be driven for rotating the vertical shaft 111 which in turn will operate the worm 113 and worm gear 114 for driving the stud 115. With the driving of the stud 115 the controlling cam 147 and gears 128, 129 will be 55 rotated for operating the shaft 130 for operating the mechanism B and the parts D to operate the figure or object 51.

Simultaneously with the starting of the machine and with the driving of the stud 115 the sprocket wheel 116, sprocket chain 117 and sprocket wheel 118 of the stud 119 will be driven, and with the driving of the stud 70 119 the eccentric disk 122 will be revolved for reciprocating the rod 123 and the ejecting plate 126 of the parts C of the mechanism B. The disk 122 is of such a diameter that with each of its revolutions the ejecting plate 75 80 will be moved between the pairs of guide plates 127, 127^a of the magazine 64 entirely across the chamber 84 for engaging and feeding each of the articles or cards A through the outlet 71 of the upper wall 67 of the magazine so that the card will be delivered between the guide plate 72 and the yieldingly movable rod 74 for being picked-up by the figure or object 51. These parts C of the mechanism B are so proportioned and their 85 operation is so timed that only one of the cards A will be delivered with each operation of the machine and at the interval following the first downward or forward tilting movement of the object 51. 90

With the driving of the stud 115 and the rotary movement of the controlling cam 147 the pin 146 of the L-shaped operating bracket 144 will follow the irregular peripheral edge of the controlling cam, beginning with the 95 starting position of the follower pin and the controlling cam, as shown in Fig. 3. When the follower pin 146 has advanced to the part 149 of the edge of the controlling cam 147 the L-shaped bracket 144 will have rotated sufficient distance for revolving the tubular shaft 15 to cause the object 51 to move forwardly toward the outlet 71 of the magazine 64 to about the position shown in Fig. 9. With the driving of the gear 129 the shaft 100 105 130 will be rotated for positioning the tooth 133 of the cam 132 in engagement with the rod 134 of the supporting plate 55 of the object 51. The rod will thereby move inwardly of the body portion 58 of the supporting 110 plate, and the V-shaped lever 136 will be moved on its pivot 136 to force the rod 137 toward the top of the head portion 60 of the supporting plate 55 against the tension of the spring 142. The rod 137 will then cause 115 the member 61 of the bill or mouth of the supporting plate and object 51 to open for gripping the card A which, as explained, has been ejected from the magazine during these 120 movements of the parts of the supporting plate 55. With the further rotation of the stud 115 and controlling cam 147 so that the follower pin 146 has moved to the part of the edge of the controlling cam, shown in Fig. 10, the bracket 144 will have moved for 125 rotating the tubular shaft 50 to cause the supporting plate 55 and object 51 to complete the first downward movement, and synchronously therewith the shaft 130 will have 130 rotated for releasing the engagement of the

tooth 133 of the cam 132 from its engagement with the rod 134 of the supporting plate 55. The tension of the spring 142 will then cause reverse movements of the rod 137 and of the member 61 of the mouth of the object to close upon the card A which in turn will be carried by the object until the object and supporting plate 55 has reversely moved to the position, shown in Fig. 11.

When the supporting plate 55 and the object 51 have moved upwardly to the position shown in Fig. 11, the stud 115 and the controlling cam 147 will have rotated to the position so that the follower pin 146 engages the part of the edge of the cam adjacent the peak of the hump or extension 150 of the cam 147, as indicated in Fig. 11 of the drawings. The supporting plate and object 51 will then have moved rearwardly approximately one-half the distance to its normal position, and the object is still holding the card A in its mouth since the shaft 130 has only rotated sufficiently to move the elliptic cam 132 so that the rod 134 is still midway between the tooth 133 and the opposite apex of the cam, which in turn causes the member 61 of the mouth to still grip the card. When the stud 115 and the cam 147 have rotated so that the follower pin 146 of the bracket 144 has moved to the peak of the hump 150 of the controlling cam 147, as shown in Fig. 12, the bracket 144 will then have been rotatively moved to rotate the tubular shaft 50 for causing the supporting plate 55 and the object 51 to complete its second downward or tilting movement. The distance of the second downward movement of the object is less than the distance of its first downward movement in order that the mouth or bill of the object will be over and in proximity to the yieldingly movable guide rods 77, 77^a which protrude through the inlet 70 of the magazine 64. During the second downward and tilting movement of the supporting plate 55 and object 51, the shaft 130 is rotated for causing the toothed cam 132 to be rotatively adjusted so that its apex opposite to its tooth 133 will engage the movable rod 134 of the supporting plate 55. The rod 134 will be moved inwardly toward the body portion 58 of the supporting plate, and the V-shaped lever 136 will be moved on its pivot 135 for moving the rod 137 against the tension of the spring 142 toward the top of the head portion 60 of the supporting plate 55. The member 61 of the mouth of the supporting plate or object 51 will then be moved on its pivot 62 to open the mouth for discharging the card A on the guide rods 77, 77^a. The card will then slide from the rods 77, 77^a through the inlet 70 of the magazine upon an inclined slideway or plate, as 192, which is provided across the forward part of the interior of the magazine, Fig. 3. The slideway 192 leads through a slot 193 in the

front wall 12 of the casing of the machine, and the slideway terminates with a delivery bent end or shelf, as 194, which protrudes from the front of the casing for receiving the dispensed card for being taken possession of by the person operating the machine with the coin.

With the discharge of each of the articles or cards A the machine continues to operate for operating the stud 115, controlling cam 147, bracket 144, shaft 130 and tooth cam 132 for causing the mouth of the object 51 to again close, as above explained, and to cause the object to return to its normal position in the upper chamber 18, and above the platform 25 of the casing. When the controlling cam 147, the follower pin 146 and the L-shaped bracket 144 have advanced to their normal positions, as shown in Fig. 3, the toothed cam 184 of the stud 119 of the parts C of the mechanism will have made a complete revolution. The toothed cam 184 is of such a circumference and of such a shape that during each of its revolutions the lever bar 182 will move on its pivot 183 to move the link 180 for causing one end of the bar 172 to also be moved on its pivot 173 so that the grooved end of the bar 172 will be first moved rearwardly of the machine against the tension of the spring 177 for enabling the arm 165 of the trip lever 164 of the switch 157 to move into the groove 174 of the bar 172 immediately following the operation of the switch for closing the circuit 102, as hereinbefore explained. When the cam 184 has completed its revolution so that the lever bar 182 reengages the tooth 185 the tension of the spring 177 will cause the grooved end of the bar 172 to reversely move. With this movement of the grooved bar 172 the shoulder 175 of the groove 174 will engage the arm 165 of the trip lever 164 of the switch 157 for moving the arm 166 and insulating plate 168 to disengage the binding post 169 from the contact plate 163 of the insulating plate 160. The electric circuit 102 will then be broken for stopping the motor 100 to stop the machine following the delivery of the card A.

In the foregoing description, I have embodied the preferred form of my invention, but I do not wish to be understood as limiting myself thereto as I am aware that modifications may be made therein without departing from the principle or sacrificing any of the advantages of this invention, therefore, I reserve to myself the right to make such changes as fairly fall within the scope thereof.

Having thus described my invention, I claim as new and desire to secure by Letters Patent:—

1. In a slot machine, in combination, a casing having a chute leading into its interior, a movable figure of a living object in

the casing, mechanism for causing the figure to rotatively move in downward and upward directions and to cause the figure to rotatively move the second time in downward and upward directions, and means carried by the figure for being operated by said mechanism for causing the mouth of the figure to open and close for picking-up an article in the casing when the figure is first moved a determined downward distance and to subsequently cause the mouth of the figure to open for discharging the article with the second downward movement of the figure.

2. In a slot machine, in combination, a casing having a chute leading into its interior, a movable figure of a living object in the casing, mechanism for causing the figure to rotatively move in downward and upward directions and to cause the figure to rotatively move the second time in downward and upward directions, and means carried by the figure for being operated by said mechanism for causing the mouth of the figure to open and close for picking-up an article in a given part of the casing when the figure is first moved a determined downward distance and to subsequently cause the mouth of the figure to open when the figure has moved a different distance with its second downward movement for discharging the article in another part of the casing.

3. In a slot machine, in combination, a casing having a chute leading into its interior, a driven shaft journaled in the casing, a movable figure of a living object on the shaft, mechanism to rotate the shaft for causing the figure to rotatively move in downward and upward directions and to cause the figure to rotatively move the second time in downward and upward directions, and means carried by the figure for being operated by said mechanism for causing the mouth of the figure to open and close for picking-up an article in the casing when the figure is first moved a determined downward distance and to subsequently cause the mouth of the figure to open for discharging the article with the second downward movement of the figure.

4. In a slot machine, in combination, a casing having a chute leading into its interior, a driven shaft journaled in the casing, a movable figure of a living object on the shaft, mechanism to rotate the shaft for causing the figure to rotatively move in downward and upward directions and to cause the figure to rotatively move the second time in downward and upward directions, and means carried by the figure for being operated by said mechanism for causing the mouth of the figure to open and close for picking-up an article in a given part of the casing when the figure is first moved a determined downward distance and to subse-

quently cause the mouth of the figure to open when the figure has moved a different distance with its second downward movement for discharging the article in another part of the casing.

5. In a slot machine, in combination, a casing having a receiving opening and an adjacent delivery opening, a chute leading into the casing, a movable figure of a living object in the casing, mechanism for causing the figure to rotatively move in downward and upward directions and to cause the figure to rotatively move the second time in downward and upward directions, and means carried by the figure for being operated by said mechanism for causing the mouth of the figure to open and close for picking-up an article delivered through the receiving opening of the casing when the figure is first moved a determined downward distance and to subsequently cause the mouth of the figure to open when the figure has moved a different distance with its second downward movement for discharging the article through the delivery opening of the casing.

6. In a slot machine, in combination, a casing having a receiving opening and an adjacent delivery opening, a chute leading into the casing, a driven shaft journaled in the casing, a figure of a living object held on the shaft, mechanism to rotate the shaft for causing the figure to rotatively move in downward and upward directions and to cause the figure to rotatively move the second time in downward and upward directions, and means carried by the figure for being operated by said mechanism for causing the mouth of the figure to open and close for picking-up an article delivered through the receiving opening of the casing when the figure is first moved a determined downward distance and to subsequently cause the mouth of the figure to open when the figure has moved a different distance with its second downward movement for discharging the article through the delivery opening of the casing.

7. In a slot machine, in combination, a casing having a chute leading into its interior, a movable figure of a living object in the casing, power driven mechanism for causing the figure to rotatively move in downward and upward directions and to cause the figure to rotatively move the second time in downward and upward directions, means carried by the figure for being operated by said mechanism for causing the mouth of the figure to open and close for picking-up an article in the casing when the figure is first moved a determined downward distance and to subsequently cause the mouth of the figure to open for discharging the article with the second downward movement of the figure, and means made ef-

fective by said mechanism to shut-off its power with the delivery of the article by the figure.

8. In a slot machine, in combination, a casing having a chute leading into its interior, a movable figure of a living object in the casing, power driven mechanism for causing the figure to rotatively move in downward and upward directions and to cause the figure to rotatively move the second time in downward and upward directions, means carried by the figure for being operated by said mechanism for causing the mouth of the figure to open and close for picking-up an article in a given part of the casing when the figure is first moved a determined downward distance and to subsequently cause the mouth of the figure to open when the figure has moved a different distance with its second downward movement for discharging the article in another part of the casing, and means made effective by said mechanism to shut-off its power with the delivery of the article by the figure.

9. In a slot machine, in combination, a casing having a chute leading into its interior, a driven shaft journaled in the casing, a movable figure of a living object on the shaft, power driven mechanism to rotate the shaft for causing the figure to rotatively move in downward and upward directions and to cause the figure to rotatively move the second time in downward and upward directions, means carried by the figure for being operated by said mechanism for causing the mouth of the figure to open and close for picking-up an article in the casing when the figure is first moved a determined downward distance and to subsequently cause the mouth of the figure to open for discharging the article with the second downward movement of the figure, and means made effective by said mechanism to shut-off its power with the delivery of the article by the figure.

10. In a slot machine, in combination, a casing having a chute leading into its interior, a driven shaft journaled in the casing, a movable figure of a living object on the shaft, power driven mechanism to rotate the shaft for causing the figure to rotatively move in downward and upward directions and to cause the figure to rotatively move the second time in downward and upward directions, means carried by the figure for being operated by said mechanism for causing the mouth of the figure to open and close for picking-up an article in a given part of the casing when the figure is first moved a determined downward distance and to subsequently cause the mouth of the figure to open when the figure has moved a different distance with its second downward movement for discharging the article in another part of the casing, and means made effective

by said mechanism to shut-off its power with the delivery of the article by the figure.

11. In a slot machine, in combination, a casing having a receiving opening and an adjacent delivery opening, a chute leading into the casing, a movable figure of a living object in the casing, power driven mechanism for causing the figure to rotatively move in downward and upward directions and to cause the figure to rotatively move the second time in downward and upward directions, means carried by the figure for being operated by said mechanism for causing the mouth of the figure to open and close for picking-up an article delivered through the receiving opening of the casing when the figure is first moved a determined downward distance and to subsequently cause the mouth of the figure to open when the figure has moved a different distance with its second downward movement for discharging the article through the delivery opening of the casing, and means made effective by said mechanism to shut-off its power with the delivery of the article by the figure.

12. In a slot machine, in combination, a casing having a receiving opening and an adjacent delivery opening, a chute leading into the casing, a driven shaft journaled in the casing, a figure of a living object held on the shaft, power driven mechanism to rotate the shaft for causing the figure to rotatively move in downward and upward directions and to cause the figure to rotatively move the second time in downward and upward directions, means carried by the figure for being operated by said mechanism for causing the mouth of the figure to open and close for picking-up an article delivered through the receiving opening of the casing when the figure is first moved a determined downward distance and to subsequently cause the mouth of the figure to open when the figure has moved a different distance with its second downward movement for discharging the article through the delivery opening of the casing, and means made effective by said mechanism to shut-off its power with the delivery of the article by the figure.

13. In a slot machine, in combination, a casing having a coin receiving chute leading into its interior, a magazine in the casing for holding removable articles and having a delivery opening and a receiving opening, a movable figure of a living object in the casing, mechanism for causing the figure to rotatively move in downward and upward directions and to cause the figure to rotatively move the second time in downward and upward directions, means operative by the mechanism for delivering the articles singly through the delivery opening of the magazine, and means carried by the figure for

being operated by said mechanism for causing the mouth of the figure to open and close for picking-up an article delivered through the delivery opening of the magazine when the figure is first moved a determined downward distance and to subsequently cause the mouth of the figure to open when the figure has moved a different distance with its second downward movement for discharging the article in the receiving opening of the magazine.

14. In a slot machine, in combination, a casing having a coin receiving chute leading into its interior, a magazine in the casing for holding removable articles and having a delivery opening and a receiving opening, a driven shaft journaled in the casing, a movable figure of a living object held on the shaft, mechanism to rotate the shaft for causing the figure to rotatively move in downward and upward directions and to cause the figure to rotatively move the second time in downward and upward directions, means operative by the mechanism for delivering the articles singly through the delivery opening of the magazine, and means carried by the figure for being operated by said mechanism for causing the mouth of the figure to open and close for picking-up an article delivered through the delivery opening of the magazine when the figure is first moved a determined downward distance and to subsequently cause the mouth of the figure to open when the figure has moved a different distance with its second downward movement for discharging the article in the receiving opening of the magazine.

15. In a slot machine, in combination, a casing having lower and upper chambers and having a coin receiving chute leading into the lower chamber, a delivery outlet leading from the lower chamber, a magazine in the casing for holding removable articles and having a delivery opening and a receiving opening, a movable figure of a living object in the upper chamber of the casing, mechanism for causing the figure to rotatively move in downward and upward directions and to cause the figure to rotatively move the second time in downward and upward directions, means operative by the mechanism for delivering the articles singly through the delivery opening of the magazine, and means carried by the figure for being operated by said mechanism for causing the mouth of the figure to open and close for picking-up an article delivered through the delivery opening of the magazine when the figure is first moved a determined downward distance and to subsequently cause the mouth of the figure to open when the figure has moved a different distance with its second downward movement for discharging the article in the receiving opening of the magazine.

ceiving opening of the magazine to the delivery outlet of the lower chamber of the casing.

16. In a slot machine, in combination, a casing having lower and upper chambers and having a coin receiving chute leading into the lower chamber, a delivery outlet leading from the lower chamber, a magazine in the lower chamber for holding removable articles and having a box like top with a delivery opening and a receiving opening, a driven shaft journaled in the casing, a movable figure of a living object held on the shaft, mechanism operative by the coin received in and ejected from the chute for causing the figure to rotatively move in downward and upward directions and to cause the figure to rotatively move the second time in downward and upward directions, means operative by the mechanism for delivering the articles singly through the delivery opening of the magazine, and means carried by the figure for being operated by said mechanism for causing the mouth of the figure to open and close for picking-up an article delivered through the delivery opening of the magazine when the figure is first moved a determined downward distance and to subsequently cause the mouth of the figure to open when the figure has moved a different distance with its second downward movement for discharging the article in the receiving opening of the magazine to the delivery outlet of the lower chamber of the casing.

17. In a slot machine, in combination, a casing having lower and upper chambers and having a coin receiving chute leading into the lower chamber, a delivery outlet leading from the lower chamber, a magazine in the casing for holding removable articles and having a delivery opening and a receiving opening, a movable figure of a living object in the upper chamber of the casing, power driven mechanism for causing the figure to rotatively move in downward and upward directions and to cause the figure to rotatively move the second time in downward and upward directions, means operative by the mechanism for delivering the articles singly through the delivery opening of the magazine, means carried by the figure for being operated by said mechanism for causing the mouth of the figure to open and close for picking-up an article delivered through the delivery opening of the magazine when the figure is first moved a determined downward distance and to subsequently cause the mouth of the figure to open when the figure has moved a different distance with its second downward movement for discharging the article in the receiving opening of the magazine to the delivery outlet of the lower chamber of the casing, and means made effective by said

mechanism to shut-off its power following the delivery of each article by the figure.

18. In a slot machine, in combination, a casing having lower and upper chambers 5 and having a coin receiving chute leading into the lower chamber, a delivery outlet leading from the lower chamber, a magazine in the lower chamber for holding removable articles and having a box like top 10 with a delivery opening and a receiving opening, a driven shaft journaled in the casing, a movable figure of a living object held on the shaft, power driven mechanism for causing the figure to rotatively move in 15 downward and upward directions and to cause the figure to rotatively move the second time in downward and upward directions, means operative by the mechanism for delivering the articles singly through the 20 delivery opening of the magazine, means
- carried by the figure for being operated by said mechanism for causing the mouth of the figure to open and close for picking-up an article delivered through the delivery opening of the magazine when the figure is 25 first moved a determined downward distance and to subsequently cause the mouth of the figure to open when the figure has moved a different distance with its second downward movement for discharging the 30 article in the receiving opening of the magazine to the delivery outlet of the lower chamber of the casing, and means made effective by said mechanism to shut-off its power following the delivery of each article 35 by the figure.

This specification signed and witnessed this 16th day of June A. D. 1926.

MICHAEL BENEDICT.
